UNITED STATES PATENT OFFICE.

JOHN V. PILCHER AND JOHN F. BABBITT, OF LOUISVILLE, KENTUCKY; SAID BABBITT
ASSIGNOR OF HIS ENTIRE RIGHT TO SAID PILCHER.

SHOULDER-STRAP HOLDER.

Application filed November 13, 1924. Serial No. 749,701.

To all whom it may concern:

Be it known that we, JOHN V. PILCHER and JOHN F. BABBITT, citizens of the United States, and residents of Louisville, in the 5 county of Jefferson and State of Kentucky, have invented certain new and useful Improvements in Shoulder-Strap Holders, of which the following is a specification.

Our present invention relates to improvements in shoulder strap holders, or lingerie clasps as they are frequently called, and aims to provide an economical article which is light and of neat and attractive appearance, which will be practically invisible under the thinnest cloth, which can be easily and quickly attached, and its manner of use 15 obvious.

With these and other objects in view, the invention includes the novel features of construction and arrangement and combination of parts hereinafter described, the precise nature and scope of our invention being defined by the claims appended hereto.

An embodiment of our invention is illustrated in the accompanying drawing, in which:—

Figure 1 is a view of one face of the clasp.

Fig. 2 is a view of the opposite face, and

30 Figs. 3 and 4 are edge views in open and closed position respectively and Fig. 5 shows the manner of attachment and use of the clasp.

Referring by reference characters to this drawing, the numeral 1 designates a bar or 35 attaching member which is designed to be sewed to the under side or inner face of the outer body garment, and is preferably composed of transparent or translucent celluloid, which while stiff enough to retain its 40 shape, is flexible or resilient enough to accommodate itself to the curve of the shoulder without discomfort to the wearer. The end portions are provided with notched edges 1^a so that the member may be quickly attached by sewing over and over, and without the 45 necessity of passing the needle through a sewing eye or opening. 2 designates the shoulder strap engaging or retaining member, which comprises a piece of elastic webbing or tape, preferably of slightly less width than the bar or member 1. One end, 2^a, is doubled back upon itself and secured to member 1 adjacent one end thereof by suitable means, such as a clip of bendable 50 metal 3 which is clamped around the bar

and tape, thereby holding the two firmly together. A similar clip 4 is clamped around the tape at a short distance from the opposite or free end, which clip is provided with a hook-shaped projection 4^a designed to engage an eye or opening 1^b in the bar, the tape extending beyond the clip to provide a portion to be grasped by the thumb and finger of the user, which extended portion preferably terminates in a reinforcing tip 65 which prevents raveling of the tape end, and also facilitates grasping.

The clip 4 is applied to the tape in such position that when the latter is in unattached position and the tape relaxed, the 70 hook rests short of the hole. When the bar has been applied to the garment and it is desired to effect engagement of the holder with the shoulder strap of the under-garment, the tape is passed under the shoulder 75 strap and stretched until the hook engages the eye of the bar, where it will be effectively held by the tension of the tape.

Having thus described our invention, what we claim is:—

1. An article of the class described, comprising a carrying member having means for attachment to a garment, and a retaining member comprising an elastic tape having one end permanently attached to said 80 carrying member adjacent one end thereof, said tape having its free portion provided with a hook for engaging an eye in the carrying member.

2. An article of the class described, comprising a carrying member having notches in the sides adjacent each end, and a holding member comprising an elastic tape having one end permanently connected to said carrying member adjacent the notches at 95 one end thereof, the free portion of said tape being provided with means for detachable engagement with the carrying member.

3. An article of the class described, comprising a carrying member having notches 100 in the sides adjacent each end, and a holding member comprising an elastic tape having one end permanently connected to said carrying member adjacent the notches at one end thereof, the free portion of said tape 105 being provided with a hook or projection for engaging an eye in the carrying member.

4. An article of the class described, comprising an elongated carrying member having garment attaching means, an elastic 110

2

tape, a metallic clip clamping one end of said tape permanently to said carrying member adjacent one end thereof, said carrying member having an eye adjacent to the other end, and a metallic clip clamped to the free portion of said tape and carrying a projection for engaging said eye, said last named clip being so positioned on the tape that when engaged with said eye the tape is stretched.

5. In a shoulder strap clip a resiliently flexible elongated non-metallic member having means adjacent its ends whereby they may be secured to the under side of a gar-

15
ment shoulder leaving the intervening portion unattached, a stretchable tape carried by the under face of said member, a clip securing one end of said tape to said member and a hook carried by the free portion of said tape and adapted to engage an eye in 20 said non-metallic member, said clip and said eye being spaced from the ends thereof whereby the same are left free for ready attachment.

In testimony whereof, we affix our signatures.

JOHN V. PILCHER.
JOHN F. BABBITT.
